UNITED STATES PATENT OFFICE.

JOHAN EWALD HOLMQVIST, OF DJURSHOLM, AND KLAS AUGUST WIDEGREN AND
EMIL HENRIK WIDEGREN, OF LIDINGO, SWEDEN.

CONTAINER FOR GRAMOPHONE NEEDLES.

Application filed March 7, 1928, Serial No. 259,725, and in Sweden March 8, 1927.

This invention relates to containers or boxes for gramophone needles and more especially to a device adapted to facilitate the picking up of needles from the container or box.

The invention consists, chiefly, in the combination with a container or box having a lid hinged thereto, of a magnet supported by said lid and being rotatable in relation there-
to.

In the accompanying drawings we have shown one embodiment of our invention. Fig. 1 is a vertical sectional view of a needle box with a picking up magnet for the needles according to this invention and Fig. 2 is a plan of the inner side of the lid of said box with the magnet. Fig. 3 shows a sectional view of a portion thereof on a larger scale.

Referring to Figs. 1 and 2 of the drawing, 20 1 is the needle box or container having a cover or lid 2 which in usual manner is secured to the box by means of a hinge 3. To the inner side of the lid 2 a magnet 4 is secured. When the lid is made of a paramagnetic material, the magnet is, preferably, to some extent magnetically insulated from the lid, for instance by means of a sheet of paper or pasteboard 5 or the like.

The magnet 4 has, preferably, the form of a horse-shoe magnet, as shown in the drawing in which case both poles 6 are bent at about right angles to the main part of the magnet and are used to pick up needles from the box, or it may have the shape of an angular bar one pole of which only is used to pick up the needles.

The magnet 4 is journalled in such manner that it can turn freely to some extent in relation to the lid or cover 2. The magnet is for such purpose not secured directly to the lid 2 but is journalled in a hinge 9 formed by a metallic strip 11 which is secured between the edge 10 of the lid and its bent portion 13 forming the hinge of the lid. The magnet 4 is easily movable in its hinge 9 so that it is turned out from the lid 2 by its own weight

when being in proper position but the movement is limited by the edges 15 on the hinge 9 as shown in Fig. 5. By this arrangement the needles picked up by the magnet are held in a proper position when the lid 2 is opened to a position as shown by dotted lines in Fig. 1 at right angles to the box and, furthermore, the needles are accessible by the magnet even if the lid is not fully closed when needles are to be picked up. When only a few needles are contained in the box it may happen that they are lying in a position in which they are not hit by the magnet poles when closing the lid. In such case it is sufficient to shake the box or to hold it in an inclined position so that the needles are moved into contact with the magnet poles.

What we claim is:

1. In combination, a box for gramophone needles, a lid hinged to said box, a magnet supported by said lid and having portions bent about at right angles to the plan of the lid, and a magnetic insulation between the magnet and the lid.

2. In combination, a box for gramophone needles, a lid hinged to said box, and a magnet supported by the lid and being rotatable in relation thereto.

3. In combination, a box for gramophone needles, a lid hinged to said box, a hinge secured to said lid, a magnet rotatably supported by said hinge and having pole pieces adapted to pick up a needle from the box and lift it to a free position when the lid is opened.

4. In combination, a box for gramophone needles, a lid hinged to said box, a hinge secured to the inside of said lid, a magnet rotatably supported by said hinge, and means to limit the movement of the magnet in relation to the lid.

In testimony whereof we have signed our names.

JOHAN EWALD HOLMQVIST.
KLAS AUGUST WIDEGREN.
EMIL HENRIK WIDEGREN.
